UNITED STATES PATENT OFFICE

155,720

DESIGN FOR A DRESS

Mildred Macpherson, New York, N. Y.

Application July 9, 1949, Serial No. 3,810

Term of patent 3½ years

(Cl. D3—26)

To all whom it may concern:

Be it known that I, Mildred Macpherson, a citizen of the United States of America, residing in New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged plan view of the sleeve, illustrating the trim in detail.

I claim:

The ornamental design for a dress, substantially as shown and described.

MILDRED MACPHERSON.
